UNITED STATES PATENT OFFICE.

WILLIAM S. HUNKINS, OF HOLLYWOOD, CALIFORNIA.

PIN TUBE.

Application filed December 4, 1925. Serial No. 73,293.

To all whom it may concern:

Be it known that I, WILLIAM S. HUNKINS, a citizen of the United States of America, residing at Hollywood, California, have invented a new and useful Pin Tube, of which the following is a specification.

This invention relates to certain new and useful improvements in so called pin tubes the purpose of which is to provide a simple construction which will admit of the tube being secured by stitching to a garment in such a manner as to prevent it from sliding endwise in the stitch loops in the event of side pull thereon.

15 In the accompanying drawing—

Fig. 1 is a relatively enlarged front elevation of my improved pin tube as it appears in use;

Fig. 2 is a rear elevation of the pin tube 20 itself;

Fig. 3 is a cross section on the line 3—3 of Fig. 2.

1 represents conventionally a fabric base upon which the tube is to be secured. The 25 tube is made of sheet metal rolled up to form a tubular portion 2, one edge of the rolled up metal being offset from the tube portion to form what I may call a securing member 3. This securing member is provided with a 30 plurality of alined slots or elongated perforations 4—4, formed by punching out the metal and rolling the same back to form folds 5—5. This act at once provides a rounded edge along the upper edge of each 35 of the openings 4—4. By this formation, I provide at least three spacer bars 6—6—6. 7—7 represent two sets of stitch loops of

thread by which the device is secured to the base 1. It will be observed that the two sets of stitch loops are spaced apart so as to support the tube from points near its ends, and it will also be observed that in the event of end strain on the tube, at least two of the spacer bars 6—6 will encounter the stitches and thus prevent the tube from sliding endwise thereon which, if permitted, would not only tend to improperly pucker the base 1, but would also bunch the stitches at one end of the tube so that the other end would hand down. By my present improvement 50 this danger is avoided and the tube is held firmly and securely in place squarely against the line of strain. By rolling back the metal to form the folds 5—5, a rounded edge is presented to that part of the stitching 55 against which the strain occurs, and hence any tendency to cut or fray the stitches is practically eliminated.

What I claim is:

1. In a pin tube construction, a rolled sheet metal tube having a laterally extending flange, said flange having a plurality of elongated perforations therein, the metal at the upper edges of said perforations being folded back to form rounded non-cutting 60 edges, said perforations being in substantial alinement.

2. In a pin tube construction, a rolled sheet metal tube having a laterally extending flange, said flange having a plurality of 65 elongated perforations therein, said perforations being in substantial alinement.

WILLIAM S. HUNKINS.
